Patented Apr. 5, 1927.

UNITED STATES PATENT OFFICE.

KALIL KARA-JOSEPH, OF PHILADELPHIA, PENNSYLVANIA.

METHOD OF RENOVATING CLOTHING.

No Drawing.

Application filed April 26, 1926. Serial No. 104,844.

My invention relates to the renovating of clothing, more particularly woolen clothing, and one object of my invention is to restore to the clothing, after a cleaning operation, 5 (or operations) the color and lustre of the original fabric.

A further object of my invention is to provide an improved process of cleaning and renovating woolen clothing whereby, after 10 complete cleansing has been effected, the color and lustre possessed by the fabric of which such clothing is made is completely restored.

The usual practice in the cleansing of garments, woolen clothing, and the like, is to wash them in a solution of soap and water, a treatment which may precede or follow 15 a bath in gasoline or other solvent; such hydrocarbon bath being designed to remove 20 larger grease spots or those of longer standing, or the cleansing operation may be conducted solely with a hydrocarbon solvent; gasoline being the solvent most frequently employed.

25 In all prior methods of cleaning, whether the washing operation referred to, or the so-called method or process of dry-cleaning, which has been employed for many years, the appearance and color of the fabric of 30 the clothing has been deadened by such washing and/or cleaning operation, and the application and subsequent removal of the hydrocarbon spirit or solvent employed, and 35 clothing cleaned by such methods never presents the appearance of the original fabric.

I have noted this condition and defect 40 for many years and as a result of many experiments which I have carried on, the method of renovating clothing, particularly 45 woolen clothing, forming the subject of my invention has been developed and perfected.

In carrying out my improved process or 50 method of renovating clothing, the garments are preferably washed in a solution of a mild or neutral soap and water to remove all dirt and stains, and following this washing operation, the garments are carefully dried and, if desired, any portions which have developed undue folds and creases may 55 be pressed. Following the drying of the clothing after the washing operation, I place them in a bath of hydrocarbon solvent, usually gasoline, whereby all grease spots and accompanying dirt not removed by the 60 washing operation, and any traces of the

soapy solution, may be completely removed. The excess gasoline or other solvent body employed is then removed and the garment allowed to dry and free itself of all traces 60 of the gasoline and/or other cleaning spirit.

I then prepare a bath for the reception 65 of the washed and dried garments, which bath is made up of gasoline or other suitable solvent and lanolin, (wool oil) in the proportion of approximately one ounce of lanolin to one quart of gasoline or other solvent; both ingredients being employed in such 70 quantities as to provide a bath sufficient in volume to treat the garments thoroughly and insure that all parts of the same shall receive this solution in equal proportions. The lanolin must be completely in solution 75 in the gasoline or other hydrocarbon solvent employed, a solution preferably effected in the presence of heat, and the mixture should be entirely homogenous so that all portions of the same contain the respective ingredients in the proportions indicated.

In the bath so prepared, the garments to be treated, are dipped, and after dipping for 80 the desired length of time, they should be squeezed for the purpose of removing the excess solution and, if desired, they may be dipped again, so as to insure an even application of the treating bath containing the 85 lanolin, and complete permeation of the same to all parts of the garment. After this treatment has been thoroughly applied, the garments are removed from the bath, squeezed, if necessary, to remove excess of 90 the treating liquid, and then hung up to dry; preferably being aired so as to remove all traces of odor due to the use of the hydrocarbon solvent.

When thoroughly dry, the garments may 95 be pressed in the usual manner and in their final condition they will have the color and lustre of the original fabric and the appearance of a new garment rather than one that has been merely cleaned in the old manner.

100 An important feature of my improved method or process resides in the fact that when woolen clothing is treated in accordance therewith, it is water resistant; that is to say, it will shed water and except under 105 conditions of greatest stress, is substantially waterproof.

110 While I have referred particularly to the treatment of woolen clothing, it is obvious that hangings, curtains, and other woolen

fabrics may be treated in the same manner and with the same result.

I claim:

- 5 1. The method or process of renovating clothing, which comprises washing the same in an aqueous solution of soap to remove stains and dirt, dipping such washed clothing in a bath consisting of a hydrocarbon solvent to remove grease spots, and finally 10 treating such clothing with a non-aqueous solution containing lanolin.
- 15 2. The method or process of renovating clothing, which comprises washing the same in a solution of soap and water, treating such washed clothing with a hydrocarbon solvent, drying such clothing, and finally treating the same in a bath consisting of a solution of lanolin and a hydrocarbon solvent.
- 20 3. The method or process of renovating woolen clothing, which comprises washing the same in a solution of a neutral soap and hot water to remove dirt and stains, treating such washed clothing with a hydrocarbon solvent to remove grease spots and insure final removal of dirt accompanying such grease spots, and then treating such clothing in a bath comprising a non-aqueous solution containing lanolin.
- 25 4. The method or process of renovating woolen clothing, which comprises washing the same in a solution of a neutral soap and hot water to remove dirt and stains, drying such clothing, treating such washed clothing with a hydrocarbon solvent to remove grease spots and insure final removal of dirt accompanying such grease spots, removing such solvent

and substantially drying the treated clothing, treating such clothing in a bath comprising a non-aqueous solution containing 40 lanolin, and finally drying such clothing.

5. The method or process of renovating woolen clothing, which comprises washing the same in a solution of a neutral soap and hot water to remove dirt and stains, treating 45 such washed clothing with a hydrocarbon solvent to remove grease spots and insure final removal of dirt accompanying such grease spots and any soapy residue from the washing operation, removing such solvent and any foreign material accompanying the same, and then dipping the same in a bath comprising a solution of lanolin and a hydrocarbon solvent.

6. The method or process of renovating 55 woolen clothing, which comprises washing the same in a solution of a neutral soap and hot water to remove dirt and stains, drying the same, treating such washed clothing with a hydrocarbon solvent to remove grease 60 spots and insure final removal of dirt accompanying such grease spots and any soapy residue from the washing operation, removing such solvent and any foreign material accompanying the same, substantially dry- 65 ing out the treated clothing, then dipping the same in a bath comprising a solution of lanolin and a hydrocarbon solvent, and finally drying and pressing such renovated clothing.

In witness whereof I have signed this specification.

KALIL KARA-JOSEPH.
